UNITED STATES PATENT OFFICE.

DAVID W. LAIRD, OF SAN FRANCISCO, CALIFORNIA.

DESIGN FOR A MASONIC JEWEL OR EMBLEM.

SPECIFICATION forming part of Design No. 14,025, dated July 3, 1883.

Application filed May 11, 1883. Term of patent 3½ years.

To all whom it may concern:

Be it known that I, DAVID W. LAIRD, of the city and county of San Francisco, State of California, have invented and produced a new and original Design for a Masonic Emblem or Jewel, of which the following is a specification.

My invention relates to a novel design for a Masonic jewel or emblem, which will be more fully described by reference to the accompanying drawing, in which the figure is a view of my design.

It consists of a Maltese cross, having the arms A A. In the central portion, where these arms meet, is a shield B, having within it the coat

of arms of the State of California. In the arms 15 of the cross are spaces for words. The cross is suspended by a link, C, from a bar, D, or it may be connected with it rigidly, and upon this stands the figure of a bear, E.

Having thus described my design, I claim— 20

The design for an emblem or jewel, consisting of a Maltese cross, with the inclosed coat of arms and the surrounding letters, together with the superposed figure of a bear, as shown.

D. W. LAIRD.
